H. SAWYER.

COMBINED HOIST AND RACK MECHANISM.

APPLICATION FILED JULY 12, 1916.

1,251,290.

Patented Dec. 25, 1917.

UNITED STATES PATENT OFFICE.

HARRY SAWYER, OF MUSKEGON, MICHIGAN, ASSIGNOR TO SHAW ELECTRIC CRANE COMPANY, OF MUSKEGON, MICHIGAN, A CORPORATION OF MICHIGAN.

COMBINED HOIST AND RACK MECHANISM.

1,251,290.

Specification of Letters Patent. Patented Dec. 25, 1917.

Application filed July 12, 1916. Serial No. 108,832.

To all whom it may concern:

Be it known that I, HARRY SAWYER, a citizen of the United States, residing at Muskegon, in the county of Muskegon, 5 State of Michigan, have made a certain new and useful Invention in Combined Hoist and Rack Mechanism, of which the following is a specification.

This invention relates to combined hoist 10 and rack mechanism.

The object of the invention is to provide a combined hoist and rack mechanism which is simple in structure, economical to manufacture, and efficient in operation.

15 A further object of the invention is to provide a structure of mechanism of the character referred to employing a rack drum and a hoist drum both mounted upon the same shaft and operated in the same direction of rotation.

20 Further objects of the invention will appear more fully hereinafter.

The invention consists substantially in the construction, combination, location and relative arrangement of parts, all as will be more fully hereinafter set forth, as shown in the 25 accompanying drawing, and finally pointed out in the appended claims.

Figure 1 is a plan view partly in longitudinal section showing a combined hoist and 30 rack mechanism embodying the principles of my invention.

Fig. 2 is a reduced view in end elevation taken on the line 2, 2, Fig. 1, looking in the 35 direction of the arrows.

The same part is designated by the same reference numeral wherever it occurs throughout the several views.

Referring to the drawing, 4 designates a 40 main operating shaft upon which are mounted a rack drum 5, and a hoist drum 6, the rack drum being keyed or otherwise connected to rotate with said shaft while the hoist drum is journaled to rotate upon said 45 shaft. A gearing for driving said shaft and the hoist drum is inclosed within the casing 7, and includes a planetary gear system comprising spur gears 2 and 3. The gear 2 is suitably connected to the hoist drum to rotate 50 therewith. The gear 3 is connected to a spur wheel 8, to rotate with shaft 4. Disposed intermediate the spur gears 2, 3, and mounted to rotate freely upon shaft 4 is the intermediate spur gear wheel 9. A rack drum 55 driving motor 12 is suitably geared to spur

gear wheel 8, through any desired arrangement of intermediate gearing, such, for example, as a pinion 18, mounted on a stud 16, and meshing with gear 8, said pinion being driven by a gear wheel 15, with which is 60 meshed a pinion 14 on the shaft of the rack motor 12. A hoist motor 13 is geared by means of pinion 17, to the intermediate spur gear 9. Carried by the intermediate spur gear 9 are a series of studs 19, which extend 65 transversely therethrough. Upon the respective ends of said studs are mounted pinions 20 and 21. The pinions 20 mesh with the spur gear 2, while the pinions 21 mesh with the spur gear 3. The operation is 70 exceedingly simple. With the hoist motor 13 idle the intermediate gear 9 is held stationary. Now, by putting the rack motor 12 into operation the spur gear wheel 8 is driven therefrom through the intermediate 75 gears 14, 15, and 18. The rotation of gear 8 imparts coincident rotation to the shaft 4, and with it the rack drum 5. At the same time spur gear 3 is rotated with spur gear 80 wheel 8. Through the intermeshing of spur gear 3, with pinion 21, the pinion 20, is also driven, thereby driving the spur gear 2, and with it the hoist drum 6, and in the same direction with the rack drum. When, however, the rack motor is idle, gear 8, and consequently also gear 3, will be held stationary. 85 Now, by putting the hoist motor into operation the intermediate gear 9, is driven from said motor through pinion 17. The rotation of intermediate gear 9 carries with it the 90 studs and since spur gear 3 is held stationary the planetary movement of studs 19 imparts axial rotation to the pinions 21, and hence also to their associated pinions 20, which by intermeshing with spur gear 2 95 drive the latter, thereby driving the hoist drum 6, without operating the rack drum.

It will be observed that the gear 3 is of smaller diameter than gear 2, and that pinion 21 is of correspondingly larger diameter 100 than pinion 20. By reason of a relative variation in the diameters of gears 2 and 3, and of correspondingly relative variation in the diameters of pinions 20 and 21, the desired gear ratio is secured. If gears 2 and 105 3 were of the same diameter and gears 20, and 21, were of the same diameter, then, in racking, the two drums would run at the same number of revolutions per minute and consequently would have to be of the same 110

diameter to run at the same peripheral speed. In this case, however, there would be no hoisting or lowering as the pinions 20, 21, would simply roll around gears 2 and 3, 5 without causing any relative motion between them. If, however, the diameter of gear 3 differed from that of gear 2, as, for example, if the diameter of gear 3 is slightly smaller than that of gear 2, and pinion 20 10 slightly smaller than pinion 21, the tooth speed of pinion 20 would be correspondingly less than that of pinion 21, and hence the gear 2, would be driven at a speed corresponding to the difference of tooth speeds of 15 the pinions 20 and 21. If the reverse of this diameter relation were employed then the gear 2 would be driven in reverse direction at a speed corresponding to the difference in tooth speeds of the pinions 20, 21.

20 The arrangement above described imparts rotation in the same direction to both the hoist drum and also the rack drum, while at the same time a desirable gear ratio intermediate the hoist motor and hoist drum is 25 secured in the planetary gear system.

Many variations and changes in the details of structure and arrangement of parts will readily occur to persons skilled in the art and still fall within the spirit and scope 30 of my invention. While, therefore, I have shown and described one specific embodiment of my invention, I do not desire to be limited or restricted to the exact details shown, but what I claim as new and useful 35 and of my own invention, and desire to secure by Letters Patent, is,—

1. In a combined hoist and rack mechanism, a main operating shaft, a rack drum mounted thereon to rotate therewith, a hoist 40 drum also mounted on said shaft to rotate thereon, means to rotate said hoist drum and shaft simultaneously in the same direction, said hoist drum being located between the rack drum and the said rotating means, and 45 means to rotate said hoist drum independently.

2. In a combined hoist and rack mechanism, a main operating shaft, a rack drum mounted thereon to rotate therewith, a hoist 50 drum to rotate thereon, a motor, gearing intermediate said motor and shaft for rotating the latter, and gearing also actuated by said motor for coincidently rotating the hoist drum in the same direction, said hoist 55 drum being located between the rack drum and the gearing.

3. In a combined hoist and rack mechanism, a main shaft, a rack drum mounted thereon to rotate therewith, a hoist drum

also mounted on said shaft to rotate thereon, 60 spur gears respectively connected to said shaft and hoist drum, a rack motor for driving one of said gears, planetary gear pinions respectively meshing with said spur gears, an intermediate gear wheel carrying said 65 pinions, said hoist drum being located between the rack drum and the said gearing, and a hoist motor geared to said intermediate gear wheel.

4. In a combined hoist and rack mechanism, a rack motor and a hoist motor, a main operating shaft, a rack drum and a hoist drum mounted on said shaft, said 70 rack drum being connected to rotate with said shaft, and said hoist drum mounted 75 to rotate upon said shaft in combination with a spur gear driven by the rack motor and connected to rotate with said shaft, a spur gear connected to rotate with said hoist drum, connected pinions respectively 80 meshing with said spur gears, a carrier for said pinions and a hoist motor geared to said carrier.

5. In a combined hoist and rack mechanism, a main operating shaft, a rack drum 85 mounted thereon to rotate therewith, a hoist drum also mounted upon said shaft to rotate thereon, a carrier mounted on said 90 shaft to rotate freely thereon, connected pinions carried by said carrier, spur gears respectively meshing with said pinions, one of 95 said spur gears connected to rotate with the hoist drum and the other connected to rotate with said shaft, a rack motor geared to the shaft to drive the same and a hoist motor geared to drive said carrier.

6. In a combined hoist and rack mechanism, a hoist drum and a rack drum, gears respectively connected to said drums, pinions connected to move in unison and respectively geared to said gears, and means 100 to drive one of said gears.

7. In a combined hoist and rack mechanism, a hoist drum and a rack drum, gears respectively connected to said drums, pinions connected to move in unison and respectively geared to said gears, means to drive one of said gears, and independent means to move said pinions.

In testimony whereof I have hereunto 110 set my hand in the presence of the subscribing witnesses, on this 29th day of June A. D., 1916.

HARRY SAWYER.
